THREAD HOLDER

Jean W. Gilbert, San Fernando, Calif.

Application October 3, 1950, Serial No. 188,203

3 Claims. (Cl. 242—126)

1

This invention relates to thread holders of the type temporarily or permanently mounted on spools of thread so as to retain the free end of the thread against unwinding when not in use.

Conventionally wooden spools for thread are notched along the top edge for insertion of the thread therein when not being wound or unwound. However, these notch segments break off easily and are generally unsatisfactory. Various devices which have been proposed for this problem have been complicated or unsatisfactory for one reason or another.

Accordingly it is an object of the invention to provide improved thread holders which are simple and economical in construction and operation.

Another purpose resides in the provision of such thread holders which can be installed on spools without blocking the central channels thereof, so that a spool can be mounted upon a pivot pin extending thru the central channel without interference with the thread holder.

A further object is to provide such an improved thread holder which is readily detachable so that it can be transferred from one spool of thread to another.

It is within the province of the disclosure to improve generally, and to enhance the utility of devices of that type to which the invention appertains.

With the above and other objects in view, which will appear as the description proceeds, the invention resides in the combination and arrangements of parts and in the details of construction and operation hereinafter described and claimed, it being understood that changes in the precise embodiment of the invention herein disclosed, may be made within the scope of what is claimed, without departing from the spirit of the invention.

In the drawings, which form part of the present specification:

Figure 1 is a perspective view of a spool of thread, centrally cut away to show one form of my thread holder mounted in the central channel thereof.

Figure 2 is a perspective view of the top of the spool and holder of Figure 1.

Figure 3 is a view of the bottom end of the same spool and holder.

Figure 4 is a side elevational view of the thread holder of Figure 1, shown apart from the spool.

In the embodiment particularly illustrated in Figures 1-4, there is provided a detachable member 10, preferably formed by bending an elong-

2

gated narrow strip of resilient material, such as steel, aluminum, organic plastic, etc. The central section of the thread holder is shaped as a generally straight shank 12, which is adapted to lie in juxtaposition to the inner peripheral surface 14 of the central channel 16 which axially traverses a conventional thread spool 18.

At opposite ends, the shank 12 is bent approximately at right angles to form a pair of generally parallel arms 20, 22 laterally extending in the same direction and adapted to overlie the outer faces respectively of the top 24 and bottom 26 disks or ends, of the spool. In this connection it is important to note that the longitudinal length 15 of the lower arm 22 is less than the inner diameter of the spool channel 16 so that it can be readily inserted completely thru the channel from the top until the upper arm 20 abuts against the top 24.

20 The holder 10 is then radially slid outward from such position until the shank 12 frictionally engages the channel wall along its entire length. When thus located, the holder is securely mounted on the spool, due to the tension or resilience 25 of the opposing arms, 20, 22 against the adjacent spool ends.

With the thread holder in place, the spool may still be easily slipped over and taken off of a spool-holding pin (not shown) such as are found 30 on a sewing machine or thread rack. This is in contrast to previous thread holders which obtain their mounting on the spool by means of a plug inserted into the central channel; this plug of course, prevents their use on a spool which is located on the conventional mounting pins as 35 the latter conventionally extend all the way thru the central channel and project above the top of the spool.

40 Preferably the outer or free end of the top arm 20 is turned down slightly to form a lip 28 which overlies the bead or edge 30 of the spool end. Accordingly the free end 32 of thread wound on the spool can be slid under this lip 28—or even moved back under the arm proper—to be releasably retained by frictional engagement until it is 45 desired to withdraw it for use.

When the thread has all been used off of the spool, the thread holder can be quickly removed from the spool by sliding the shank 12 toward 50 the opposite side of the channel and then withdrawing the member from the top of the spool. With equal facility it can then be mounted on another spool.

Thus it will be seen that I have produced a 55 thread holder, which is of comparatively simple

and economic construction, is easy to install and remove, and will perform its function in a highly effective manner, without interfering with the utilization of the thread or spool itself. My thread holder will not readily wear out or get out of adjustment and the spools on which it is placed—either by the manufacturer or user—can be transferred from one spool holder to another without interference with the thread holder or danger of loss thereof.

While I have herein shown and described my invention in what I have presently conceived to be the most practical and preferred embodiment, it is recognized that departures may be made therefrom within the scope of my invention, which is not to be limited to the details disclosed herein, but is to be accorded the full scope of the claims so as to embrace any and all equivalent devices.

The invention having been herein described, what I claim as new and desire to secure by Letters Patent is:

1. A thread holder of the character described comprising: a resilient member having a central shank adapted to be received thru the central channel of a spool and to be lodged in juxtaposition with the wall thereof, a pair of generally parallel side arms extending respectively from opposite ends of said shank and adapted to releasably engage opposite ends of said spool, one of said arms being slightly less than the diameter of such spool channel, and the other of said arms being adapted to extend adjacent an edge of the spool so as to releasably retain a thread between the arm and the spool.

2. A thread holder of the character described comprising a resilient member having a central shank adapted to be received thru the central

channel of a spool and to be lodged in juxtaposition with the wall thereof, a pair of generally parallel side arms extending respectively from opposite ends of said shank and adapted to releasably engage opposite ends of said spool, one of said arms being slightly less than the diameter of such spool channel, and the other of said arms being adapted to extend adjacent an edge of the spool and having a projecting lip adapted to overlie the same so as to releasably retain a thread between the arm and the spool.

3. In combination with a thread spool, the improvement comprising: a thread holder formed with an elongated arm formed of resilient material, having a free end disposed adjacent an edge of the spool so as to releasably retain a thread therebetween, a shank connected to the other end of said arm and disposed in the central channel of the spool in lateral registration with the wall thereof, and another arm having a length less than the diameter of said channel and extending from the opposite end of the shank in frictional engagement with the spool end, whereby the thread holder is detachably retained on the spool.

JEAN W. GILBERT.
